CLAIM

(57) The ornamental design for a go kart, as shown and described.

DESCRIPTION

FIG. 1 is a top, front and left side perspective view of go kart, showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

The broken lines in the drawings illustrate the portions of the go kart, which form no part of the claimed design.
